Primary Examiner — Dana Meyrow(74) Attorney, Agent, or Firm — Egbert, McDaniel & Swartz, PLLC(57) CLAIM

The ornamental design for a bottle, as shown and described.

DESCRIPTION

FIG. 1 is a perspective view of a bottle showing my new design;

FIG. 2 is a front view thereof, the rear view being identical; FIG. 3 is a side view thereof, the opposing side view being identical; and,

FIG. 4 is a top view thereof.

The unclaimed inside sidewall surface of the bottle has been omitted in FIGS. 1 & 4 for ease of understanding. The broken lines in the drawings illustrate the portions of the bottle that form no part of the claimed design.
